[57] CLAIM

The ornamental design for a paperweight or similar article, as shown and described.

DESCRIPTION

FIG. 1 is a front perspective view of a paperweight or similar article showing my new design;

FIG. 2 is a left perspective view;

FIG. 3 is a top plan view; and

FIG. 4 is a right perspective view thereof.

The bottom of the article is plain and unornamented.

FIG. 1.

FIG. 3.

FIG. 2.

FIG. 4.
